[57] CLAIM

The ornamental design for a physical exerciser, as
shown and described.

DESCRIPTION

FIG. 1 is a perspective view of a physical exerciser
showing my new design;

FIG. 2 is a side elevational view thereof, the opposite
side being a mirror image of the view of FIG. 2;

FIG. 3 is a front elevational view thereof;

FIG. 4 is a rear elevational view thereof;

FIG. 5 is a top plan view thereof; and

FIG. 6 is a bottom plan view thereof.
